UNITED STATES PATENT OFFICE.

LEON O. DOW, OF MALDEN, MASSACHUSETTS.

MILK-SAFE.

1,238,114.

Specification of Letters Patent. Patented Aug. 28, 1917.

Application filed March 16, 1915. Serial No. 14,669.

To all whom it may concern:

Be it known that I, LEON O. Dow, a citizen of the United States, residing at Malden, in the county of Middlesex, in the State of Massachusetts, have invented a certain new and useful Improvement in Milk-Safes, of which the following is a specification, reference being had to the accompanying drawings.

10 The object of this invention is to provide a convenient and reasonably cheap receptacle for bottled milk; said receptacle being specially designed to be located on the outer side of a house and to be opened only from 15 the inner side, as I shall explain more fully later; my purpose being to thus provide a depository in which a milkman may place a full bottle of milk and, at the same time, take away an empty bottle, the depository 20 or safe being so constructed that the milkman can lock up a full bottle but no one can unlock it except with the knowledge and aid of the housewife.

My invention is illustrated in the annexed 25 drawings, Figure 1 being a perspective view of a milk safe embodying my present improvements, as it appears when closed and locked, Fig. 2 is a similar view of the said safe with both of its doors opened and Fig. 3 is a like view with one or its doors open and the other door closed.

Fig. 4 is a horizontal, sectional, view of the safe housing taken on the line 4—4 of Fig. 1. Fig. 5 is a top view of the left hand 35 door (22). Fig. 6 is an elevation of the upper portion of the door 22 as viewed from the inner side of said door. Fig. 7 is a view, in elevation, of the latching, and latch-operating, mechanism which is mounted upon 40 the partition which divides the safe housing into two compartments, as it appears when the door of the left hand compartment is open and the door of the right hand compartment is closed.

45 Fig. 8 is a similar view showing said mechanism as it appears when the left hand door is closed and the right hand door is automatically sprung open.

Fig. 9 shows said mechanism as having 50 been operated by pulling the knob 25 in order to open the left hand door.

My described safe may be constructed of sheet metal, or other substantial material, of box form having two compartments, one 55 of which is indicated by the reference numeral 20 and is specially adapted to receive

a full bottle of milk while the other compartment 21 is specially provided to receive one or more empty bottles.

The compartment 20 has a closure 22 of 60 door form that is hinged to the box-like casting or housing 23, and the compartment 21 has a door 24 that is also hinged to the housing 23.

Provision is made, as I will describe in detail, for locking both doors in their closed positions, the intended operation of said doors being as follows. The empty bottle is placed by the housewife in the compartment 21 and the door of that compartment 65 is closed and automatically locked by a spring-actuated bolt; the door of the other compartment (20) being, however, left unlocked. When the milkman arrives with the daily supply of fresh milk he places the bottle in the compartment 20 and, as he closes the door, the door is automatically locked and, by the same action, the door 24 is caused to automatically unlock and swing 70 open, thus allowing the milkman to reach in and remove the empty bottle or bottles.

Meanwhile the door 22 is fastened in its closed position and remains so until the housewife is ready to take in the full bottle of milk when she pulls a knob or ring 75 25 located inside the house, and thus operates mechanism which unlatches the door 22 which then swings open automatically and she then goes outside and takes the full bottle from the compartment 20. After the 80 bottle has been emptied and cleansed she takes it outside and places it in the compartment 21 and closes the door 24 thus locking up the empty bottle until such time as the milkman comes again with a full bottle; the compartment 20 being meanwhile left unlocked, as stated above, to receive the said 85 full bottle.

I will now describe specifically the novel mechanism by means of which I am able to 90 accomplish the desirable results recited above; said mechanism being located mainly on the partition wall 26 which divides the housing into the two compartments 20 and 21.

Within the compartment 20 is a bar 27 that is preferably of curved form approximating the curve of the milk bottle, said bar being hinged at 27^a and having at its free end a stud-like extension 27^b that projects 100 through a slot in the partition wall into the compartment 21.

The said curved bar 27 is so positioned that, when a bottle is placed in compartment 20 and is pushed back in said compartment by the closing of the door, the bar is correspondingly pushed rearward thus changing the position of its extension 27^b.

The top portion of door 22 is provided, near its hinge, with an extension 22^a which is notched as at 22^b to hook over a latch 28 that is fulcrumed at 28^a on the partition 26, (when the door is closed) in order to lock the door in its closed position and said door is also provided with a second projection 29 which also extends through the said partition wall when the door is closed, and is adapted to coöperate with the upper end portion of a bar 30 which is fulcrumed at 30^a and extends downward a considerable distance and carries a fixed pin 30^b which is adapted to coöperate with a latch 31 that is fulcrumed at 31^a and is formed with a hook 31^b that is suitably positioned and shaped to drop into a staple 32 on the door 24, when the latter is closed, and thus lock the said door in its closed position. The latch 31 rests then on the pin 30^b and when the bar 30 is swung laterally by the closing of door 22 and the consequent engagement of the projection 29 with the upper end of said bar 30, the pin 30^b raises the latch 31 a distance sufficient to withdraw the hook 31^b from the staple 32 and thus permit the door 24 to be pushed open by a leaf spring 33 secured to the housing, or to the partition wall as may be most convenient.

The latch 31 is formed with a second hook 31^c which, when the said latch-bar is raised, as I have just described, is moved into position to drop into the staple 32 upon a slight lateral reflex movement of 31 and the said hook 31^c then operates to hold the door 24 closed until such time as a bottle is placed in compartment 20 and the door 22 is closed, when the lever 34 is rocked out of blocking engagement with the lower end of the bar 30 which latter is then rocked by the door-projection 29, thus raising the hook 31^c out of the staple and permitting the door 24 to swing open and expose the empty bottle.

50 The stud-like projection 27^b on the curved bar 27 lies in a diagonal slot 34^a in a lever 34 which is fulcrumed at 34^b, the arrangement of stud and slot being such that when the stud is moved rearward by the entrance 55 of a full bottle in compartment 20, the lever 34 will be rocked on its fulcrum from the position shown in Fig. 7 to the position shown in Fig. 8 thus moving the other end of said lever 34 out of the path of the lower end 60 of the bar 30 and thus permitting the latter to be swung on its fulcrum in order that the said lever 34 may raise the latch hook 31^b out of the staple 32. Until the lever 34 is thus moved out of the path of lever 30 the latter

cannot be swung so as to move the latch 31^b 65 and it will therefore be obvious that the unlatching of door 24 is dependent upon two operations; first, the movement of lever 34 by the projection 27^a upon the entrance of a bottle in compartment 20 and, second, the 70 swinging of lever 30 by the extension 29 when the door of said compartment 20 is closed. Thus it will be seen that the compartment 21 cannot be opened by simply moving the curved bar 27 nor by simply 75 closing the door 22 but that both actions must be performed practically simultaneously, and that is only possible by placing in compartment 20 a bottle which will be pushed against the curved bar 27 by the closing of door 22.

When the housewife wishes to take in the full bottle she first pulls the knob 25 which is connected to a lever 35 which is fulcrumed at 35^a and is retained yieldingly in its normal position by a spring 36, the upper end of the lever 35 being located just below the latch 28, already referred to, and in such relation to said latch 28 that, when lever 35 is rocked by the pulling of knob 25, the latch 90 28 will be rocked out of engagement of the hook 22^a and the door 22 will thus be released and allowed to swing open, the other door being simultaneously unlatched.

She then goes outside and removes the 95 full bottle from compartment 20, and leaves said compartment unlocked.

Pivoted to the end of lever 34 is a bar 37 whose upper end is bifurcated or slotted and straddles a pin 38 on the latch 28, the length of the slot being such that, when the bar 37 is moved upward by the rocking action of the lever 34, the pin 38 is engaged by the lower end wall of said slot and the latch 28 is held out of engagement with the hook 22^a (see Fig. 7). Assuming that the door 22 is open and the door 24 closed and a milk bottle is placed in compartment 20 and moved rearwardly so as to swing the bar 27, the lever 35 will be swung downwardly, after which the door 22 is swung to its closed position with the hook 22^a engaged with the lever 28 and the projection 29 with the bar 30. As the bar 30 swings inwardly, the pin 30^b lifts the latch 31 so that the hook 31^b 110 releases the staple 32, whereupon the door 24 opens under the action of the spring 33. The empty bottles can now be removed, but the full bottles must remain in the compartment 20 as long as the door 22 remains locked. To release the door 22 it is necessary to rock the lever 35, which action swings the latch 28 from engagement with the hook 22^b.

Having thus described my invention, I 125 claim as new and wish to secure by Letters Patent:—

A milk safe comprising a housing having

two compartments, a closure for each compartment, a bar and latch pivotally mounted between the compartments, a lever associated with the bar and latch for locking one of the closures, a pair of projections carried by the other closure, one of said projections being adapted to engage the bar to actuate the

same to release the latch, the other projection being adapted for locking engagement with said lever to lock the associated closures. 10
